[57] CLAIM

The ornamental design for a baseball equipment storage and organizer case, as shown and described.

DESCRIPTION

FIG. 1 is a front perspective view of the baseball equipment storage and organizer case from one end thereof, showing my new design;

FIG. 2 is a rear perspective view from an opposite end thereof;

FIG. 3 is a front elevational view thereof;

FIG. 4 is a rear elevational view thereof;

FIG. 5 is a side elevational view thereof;

FIG. 6 is an elevational view of an opposite side thereof;

FIG. 7 is a top plan view thereof;

FIG. 8 is a bottom plan view thereof; and,

FIG. 9 is a front elevational view thereof wherein a front cover has been removed from a storage portion and the front portion and storage portion secured to a fence, the fence, helmets and bats being shown in broken lines for illustrative purposes only and forming no part of the claimed design.
